UNITED STATES PATENT OFFICE.

JOHONNAS TEN BRINK, OF HOLLAND, MICHIGAN.

TRUCK-STARTING IMPLEMENT.

1,358,347.

Specification of Letters Patent.

Patented Nov. 9, 1920.

Application filed April 13, 1920. Serial No. 373,605.

To all whom it may concern:

Be it known that I, JOHONNAS TEN BRINK, a citizen of the United States, residing at Holland, in the county of Ottawa and State 5 of Michigan, have invented certain new and useful Improvements in Truck-Starting Implements, of which the following is a specification.

My invention relates to improvements in 10 starting devices for fire department trucks, and kindred vehicles, and its objects are: first, to provide a means whereby the weight of the truck will be relieved upon the tires, and, second, to provide a means whereby the 15 movement of the clutch lever will provide a means for moving the truck forwardly before the power has been applied from the motor, and thus the strain upon the motor parts may be greatly lessened.

20 I attain these objects by the mechanism shown in the accompanying drawing, in which Figure 1 is a side elevation, Fig. 2 is a back elevation, and Fig. 3 is a front elevation of my device, Fig. 4 is a longitudinal 25 section of the lower parts of a truck with my device in place. Fig. 5 is a plan of the supporting cap of my device showing the manner of attaching the same, and Fig. 6 is a bottom plan of the shoe showing 30 serrations to prevent slipping.

Similar reference characters indicate similar parts throughout the accompanying drawings.

This implement consists of a supporting 35 frame 1 with an extensible screw end 8 thereon, said end having a cap 9 thereon arranged to engage the lower side of the axletree 15 to raise and support the same. I have shown a lever 20 passed through the 40 hole h for operating the screw 8, but other means may be used as desired. The supporting frame or standard 1 has a broad foot 14 made integral therewith, said foot being curved practically upon the radius indicated at B so that as it tips over it will be 45 inclined to roll upon the foot. It is better to have the lower surface of the foot serrated, as indicated in Fig. 6 so it will not slip when forcing the truck forward, as 50 hereinafter described.

To complete the device I pivot a long brace, 2, to the standard 1 at a , and to short braces 3 at b , the lower ends of the short braces being connected with the standard 1 5 by means of a cross brace 4 pivotally connected at c and g , the continuous brace 2-3

being held in alinement, when in use, by the short cross brace 5, pivoted to the brace 2 at d , and to the trip 6 at d' , the trip being pivoted to the standard, through the projection 11, at e , and has a cable 7 connected with it at f . The pivotal point d' is slightly lower than a direct line, $x-x$, between the pivots d and e so that normally the brace 5 and the trip 6 will hold the brace 2-3 rigidly in place, but if the cable 7 is drawn upwardly to D the end f of the trip 6 will be raised sufficiently to carry the pivotal joint d' above the line $x-x$ and draw the braces inwardly, as indicated at A, breaking the 60 support of the braces 2-3 and allowing the standard to fall forwardly, as indicated at A', the braces and trip folding against the standard, as indicated at C. It is understood that when in use the standard holds 65 the wheels 19 some distance from the supporting element, as a floor, so that when the trip is sprung and the standard falls forward the entire truck is carried forward, as indicated by the dotted lines of the wheel 70 19, giving it a forward impetus independently of the truck driving motor, not here shown.

I prefer that the base 13 be made broad, and that the shoe 14 be reinforced by web 85 braces 12 to insure perfect rigidity of construction.

To operate this device a lever 16 is pivotally mounted upon the truck frame with the lower end, i , in position to receive a loop on 90 the end of the cable 7, the upper end of said lever being connected with some corresponding lever, as 18, by a cable or rod 17. 18 may be the clutch lever, if desired, or any other available mechanism, so that its 95 forward movement will cause the lever 16 to pull upwardly upon the cable 7 and actuate the trip 6, as, and with the effect hereinbefore described. The forward movement of the truck will cause the arm i of the lever 100 16 to become disengaged from the cable, thus averting the danger of dragging the device with the truck.

10 is a slot through the standard 1 for the passage of the trip 6 and the cable 7. 105

It will be understood that, if desired, the standard 1 may be made to use without the screw 8, and the truck elevated into position to apply the starter by means of an ordinary jack, or a lever, and the starter placed 110 in position, but I greatly prefer the construction herein shown as it converts the imple-

ment into a jack as well as a starter, and thus renders it much more convenient of use than if other implements were necessary to make it available for the purpose for which it is designed.

The free end of the trip 6 should overlap the braces 5 sufficiently so the connected ends of the two cannot drop below the position shown in Fig. 1, and thus render it impossible for the braces 2-3 to fold or break until the trip is drawn upwardly sufficiently to carry the braces 2-3 out of alinement. The cap 9 is made revolubly adjustable upon the bolt 8, as indicated in Fig. 5.

15 What I claim as new in the art, is:

1. In a starting device for trucks, a standard, an adjustable cap thereon, a long brace pivotally connected with the standard near its upper end, a short brace pivotally connected with the lower end of the long brace, a cross brace pivotally connected with the lower end of the short brace and with the standard, a trip pivotally connected with the standard, a short cross brace pivotally connected with the long brace and with the trip, and means for actuating the trip to cause the braces to collapse and the starter to incline over and start the truck moving forwardly.

2. In a starting device for trucks, a standard, a screw threaded bolt mounted in the upper end of the standard, a revolubly adjustable cap on said bolt, means for revolving said bolt to raise and lower the cap, collapsible braces pivotally connected with the standard to support the standard rigidly, a trip connected with the braces, a trip lever connected with the truck frame, and means for actuating the trip from the trip lever

causing the braces to collapse and the standard to fall over and force the truck forwardly.

3. In a starting device for trucks, a standard, collapsible braces pivotally connected with one side of the standard, a trip pivotally connected with said braces and with the standard, a screw threaded bolt mounted in the upper end of the standard, means for revolving said bolt, an adjustable cap on said bolt, a trip lever pivotally mounted upon the truck frame, a cable connecting this lever and the trip, and means for actuating this lever from the clutch lever of the truck to cause the braces to collapse and the truck to be forced forwardly by the movement of the starter.

4. In a starting device for trucks, a standard, collapsible braces pivotally connected with the standard, a shoe formed upon the lower end of the standard and curved convexly on its lower surface, serrations formed on said surface to prevent slipping, a trip pivotally connected with the frame and with the braces, an actuating lever pivotally mounted on the truck frame, a cable connecting one end of said lever with the free end of the trip, and a cable connecting the actuating lever with the clutch lever of the truck in such a manner that the forward movement of the clutch lever will cause the braces to collapse and starting device to roll forwardly upon its shoe and move the truck forwardly.

Signed at Holland, Michigan, April 9, 1920.

JOHONNAS TEN BRINK.
